UNITED STATES PATENT OFFICE.

MANFRED VON ARDENNE, OF BERLIN, GERMANY, ASSIGNOR TO RADIO CORPORATION OF AMERICA, A CORPORATION OF DELAWARE.

DOUBLE-GRID THERMIONIC TUBE.

Application filed December 17, 1926, Serial No. 155,544, and in Germany December 1, 1925.

It is known that tubes equipped with two (and, if desired, more grids) can be used in what is known as the "space-charge" and the "protective grid" connection. 5 It is also known, that, according to the particular use of the tube, either the one or the other kind of connection offers greater advantage. Examining the conditions for most favorable amplification of high-frequency alternating current, on the one hand, and low-frequency alternating current, on the other hand, it is found that one and the same tube is able to give optimum conditions for both services only by the adoption of a 10 special form of construction. The two-grid tubes heretofore used either in space-charge or protective grid connection, so far as their working characteristics are concerned especially the "inverse amplification factor," are 15 nothing but a matter of chance, so that, for instance, while they may be particularly advantageous for audio-frequency amplification in the so-called protective grid connection, they are unable to give at the same time optimum conditions for radio frequency amplification in the space-charge connection. 20

Now, the special type of tube hereinafter to be described is so designed that it happens to give best results for low frequency amplification in the protective grid arrangement, while offering most advantages for radio frequency amplification in the space-charge connection. Optimum inverse amplification factor (Durchgriff), to be sure, is not a constant 30 magnitude, although tests have shown that inside the customary broadcast wave range, i. e., between 200 and 800 meters approximately, an inverse amplification factor of 10% proves best. But an especially favorable 35 audio-frequency amplification is obtained with the same tube in protective grid connection, with an inverse amplification factor of 1%. The construction of the tube will be described hereinafter in more detail. 40

45 As will be seen from what precedes, the most particular feature of the construction of the present tube resides in that the same exhibits an inverse amplification factor of 10% when in space-charge connection, and an inverse amplification factor of 1% when arranged in protective grid connection. 50

In the accompanying drawing Fig. 1 shows somewhat diagrammatically an elevation view of my tube and,

Fig. 2 shows the connections of a circuit 55 utilizing my tube.

The construction of the tube shown in Fig. 1 is as follows: The length of the filament 1 is about 2 cm. The filament is surrounded concentrically by two grids 2 and 3 60 and one plate 4. The diameter of the inner grid 2 is 2.7 mm., that of the outer grid 3 6.2 mm., and that of the plate 10 mm. The inner grid comprises 13 turns, the outer one 18 turns, the wire diameter of both grids being 65 about 0.2 mm.

Although the particular dimensions as hereinbefore indicated are merely indicated to attain the aim of the invention, the basic idea of the latter is more general. For, as 70 could be shown theoretically, it is always possible to satisfy simultaneously two conditions with one two-grid tube, that is, a definite inverse amplification factor D^1 with the tube arranged in space-charge connection, 75 and another inverse amplification factor D^2 also to be chosen ad lib., with the tube arranged in protective-grid connection, provided that D^2 does not exceed D^1 . The means adapted to insure the desired inverse amplification factors are themselves well known, 80 and they consist in variable relative grid and plate resistances, variable number of diameters of grid wires, and other secondary and less important factors. 85

Now, while in the conventional types of two-grid tubes, the conditions as to inverse-amplification factor ratios between space-charge and protective-grid connection were a mere matter of chance, these relations according to the present invention, as above pointed out are to be chosen in such a manner that for the two modes of circuit arrangement and connection the working conditions of the tubes are so that there result optimum 90 dimensions for the various fields of application. It is thus possible to make one and the same tube for different purposes, which represents a great manufacturing advantage 95 and also a saving in tubes, indeed, only one-half the number of tubes is required since they are usable for a two-fold purpose. 100

My tubes may be utilized for example, in a circuit of the type shown in Fig. 2. Radio frequency energy from antenna 6 is fed into 105 the tuned oscillation circuit 7, potential variations across this tuned circuit being fed across the radio frequency grid 2 and fila-

ment 1 of my improved tube indicated by numeral 5 in that figure. The radio frequency output of tube 5 is shunted across an audio frequency transformer 8 by means of condenser 9 and is fed into a second tuned circuit 10, which in turn feeds a detector circuit 11. By means of audio frequency transformer 12, audio frequency variations and potentials are impressed across the grid 3 and filament 1 of my tube 5. The resulting amplified audio frequency current variations appearing in the plate circuit of tube 5 are fed by means of transformer 8 into a suitable sound producing device 13. In this manner my improved tube is used both for radio frequency amplification and for low frequency amplification.

I claim as my invention:

A thermionic tube comprising a straight filament substantially 2 centimeters long, a pair of concentric coiled grids about the filament composed of wire whose diameter is substantially 2 millimeters, the inner grid having substantially 13 turns and a diameter of substantially 2.7 millimeters, the outer grid having a diameter of substantially 6.2 millimeters and having substantially 18 turns, the inner grid being adapted for causing high frequency variations in the electron stream of the tube, and the outer grid being adapted for causing low frequency variations in the electron stream of the tube.

MANFRED VON ARDENNE.
